UNITED STATES PATENT OFFICE.

JOHN P. ANGUS, OF TONAWANDA, NEW YORK.

AUTOMATIC TRAIN-CONTROL DEVICE.

1,423,385.

Specification of Letters Patent.

Patented July 18, 1922.

Application filed March 20, 1919. Serial No. 283,792.

To all whom it may concern:

Be it known that I, JOHN P. ANGUS, a citizen of the United States, residing at Tonawanda, in the county of Erie and State 5 of New York, have invented certain new and useful Improvements in Automatic Train- Control Devices, of which the following is a specification.

My invention relates to improvements in 10 automatic train control devices, and it consists in the constructions, combinations, and arrangements herein described and claimed.

An object of my invention is to provide an 15 automatic train control device including electrically operated braking mechanism, said electrically operated mechanism being normally energized when certain semaphore arms mounted upon standards at the sides of the tracks, are at a danger indicating 20 position, certain electrical connections being provided whereby the brake operating mechanism is normally at rest and deenergized when the semaphore arms are at a safety indicating position.

Another object of the invention is to provide 25 an indicator included in one of the circuits which by its position will apprise the engineer of the position of any particular semaphore arm at the side of the track when 30 a new block is entered.

Another object of the invention is to provide 35 a device of the character described including a novel motor controlling device including movable rack members for operating a brake lever and cam devices for automatically throwing an actuating gear out of engagement with the racks to cause the discontinuance of the rotation of the motor.

Other objects and advantages will appear 40 from the following specification, reference being had to the accompanying drawings, in which:

Figure 1 is a diagrammatic perspective view showing the electrical connections to 45 the various devices forming a complete embodiment of my invention, a semaphore arm at the side of the track being shown in a danger indicating position,

Figure 2 is a cross-section of the motor 50 operated, brake actuating devices taken substantially on the line 3—3 of Figure 3,

Figure 3 is a perspective view of the brake operating motor actuated devices,

Figure 4 is an elevation of an indicating device located in the engine cab, 55

Figure 5 is a detail cross section of an automatic switch,

Figure 6 is a cross section on the line 6—6 of Figure 5, and

Figure 7 is a diagrammatic view showing 60 the circuits involved in this invention.

By reference more particularly to Fig. 1 of the drawings, it will be observed that a locomotive engine 1 indicated in dotted lines in the drawings, is provided with wheels 2 65 supported in turn upon an axle 3. The wheels 2 are movable upon the track 4 one of the rails thereof acting as a branch of an electric circuit hereinafter referred to.

A dynamo 5 supported in any suitable 70 manner upon the locomotive 1, is driven by a belt 6 from a pulley 7 on the axle 3. Current from the dynamo 5 is conducted over wires 82 and 83 which form part of a circuit to be explained hereinafter. 75

A semaphore standard 12 is mounted at one side of the track 4 and includes an enlarged hollow base 13. The semaphore standard 12 is provided with a laterally projected arm 14 which carries a suitable insulator 15 in which a bracket 16 is mounted. The bracket 16 includes the laterally extended clamp arms in each of which one end of metallic conductors 17 and 18 respectively is securely held. A semaphore arm 19 is fulcrumed at 20 upon the standard 12 and the semaphore arm 19 carries a quadrant in which colored panes 21 are fixed so that the positions of the semaphore arm 19 may be rendered visible by a suitable illuminant as 85 90 at night.

The metallic conductors 17 and 18 mounted in the clamps of the bracket 16 are separated at their adjacent ends so that there will be no continuation of an electrical current therebetween. While but one semaphore standard 12 is illustrated in the drawings, in actual practice there will be one semaphore standard 12 at the beginning and marking the entrance to each block. The 100 semaphore arm 19 will be actuated in any suitable manner so as to indicate whether or not the block is clear, said indication being shown by the position of the semaphore arm 19, which when in its danger indicating position will be disposed at right angle to the 105

standard 12 as shown in Figure 1, and when in its safety indicating position will be dropped and inclined at an angle to the standard 12.

5 A local circuit is located at each semaphore standard 12, the semaphore arm 19 acting as a switch for closing one branch thereof. For this purpose the semaphore arm 19 carries a contact 22 which is connected by the wire 23 with one pole of a local battery 24. The other pole of the local battery 24 is connected through the medium of a wire 25 to the adjacent rail 4 of the track. The contact 22 is adapted to cooperate with 10 a fixed contact 26 mounted upon the semaphore standard 12 and insulated therefrom as at 27. The fixed contact 26 is connected with the wire 17 of the anterior block through the medium of a connecting wire 28.

20 The anterior block above referred to is thus designated as a matter of convenience in describing the operation of the device. It will be observed that the locomotive 1 is movable toward the left in Figure 1 upon 25 the tracks 4. The divisions or blocks represented by the separated wires 17 and 18 control the operation of an air brake lever upon the engine by conducting current from the local battery 24 at certain times to said 30 brake operating mechanism. It will thus be understood that as the locomotive enters a block represented by the isolated wires 17 and 18 that a different operation of the brake actuating mechanism may take place depending upon the position of the respective 35 semaphore arm 19 at the entrance of the successive blocks.

A trolley 29 is in engagement with the wires 17 and 18 and serves to conduct current 40 from the local battery 24 to the brake operating mechanism. The trolley 29 is mounted upon an arm 30 supported in turn upon a suitable base 31 and has the usual buffer spring 32 whereby the trolley 29 is 45 clipped into tight engagement with the wires 17 and 18. An automatic switch 33 is pivotally mounted as at 44 in the housing 35 as clearly shown in Figure 5.

50 A switch arm 33 is preferably constructed of copper and includes the metallic armature pieces 36 which are adapted to be attracted by an electro-magnet 37 when the latter is energized. A spring 38 secured at one end to the armature 36 and at the other 55 end to a stud 39, tends to normally pull the switch 33 toward the left in Figure 5 and out of engagement with a contact 40. The contact 40 is however not electrically active but acts simply as an abutment member for 60 the switch arm 33 when the latter is drawn forwardly through the influence of the electro-magnet 37.

The electro-magnet 37 is energized when the semaphore arm 19 is in its safe indicating position, and when the movable contacts

22 thereon come into engagement with the fixed contact 26. At this time one branch of the local circuit previously referred to is closed by the contacts 22 and 26, and when the trolley 29 enters into the block represented by local circuit, the current from the local battery 24 will flow over the wire 25 to the track 4, through the tracks 4 and the metallic portions of the locomotive to a wire 41 which it will be observed is grounded upon one of 75 the axles 3 of the locomotive.

The current in flowing over the wires 41 passes on to the electro-magnet 37 causing the windings thereof to be energized, drawing the armature 36 over against the cores 80 of the magnet and into engagement with the fixed contact 40 in the automatic switch box 35. The current from the local battery 24 in leaving the coils of the electro-magnet 37, 85 will return to the negative pole of the battery 24 over the wire 42, through the trolley arm 30, the trolley 29, and back to the wire 17 from whence it will pass over the wire 28 to the contacts 22 and 26 and finally returning to the negative pole of the local battery 90 24. The brake actuating mechanism is thus not affected.

A train pipe valve 43 is controlled by a lever 44 which when rotated to its proper position through the medium of the electrically operated brake actuating mechanism, serves to relieve the air pressure in the train pipe 45. A link 46 having bifurcated ends 47 and 48 is connected to the lever 44 and to the ear 49 of a rack frame 50 respectively. 100

The rack frame 50 includes the upper and lower rack surfaces 51 and 52. The rack frame 50 is bridged by members 53 and a single brace member 54. The bridge members 53 support a guide or track 55 which ends in a curved portion 56. The bridge member 54 supports a cam guide 56' which has an overhanging flange 57. The lower curved portion of the cam guide 56 merges 110 with a forward projecting beak 58. The beak 58 is disposed in such cooperative relationship with the curved end 56 of the guide 55, that when the end of an actuating shaft 59 is moved into engagement with the 115 curved portion 56, the shaft 59 is transferred from the guide 55 to the plane therebelow. In speaking of transferring the shaft 59 from the upper to the lower plane, it is to be understood that the shaft 59 is 120 not in itself moved, but that the rack frame 50 is moved, this being accomplished in a manner presently to be described.

A cam surface 60 at one end of the rack frame 50 merges with a shoulder 61 which 125 is adapted to ride upon the upper surface of a slate base 62. The forward portion of the rack frame 50 rides upon a track 63 on which an approach 64 is provided. The rack frame 50 is adapted to be moved to 130

ward the right in Figure 3, and the cam 60 is adapted to ride upon the approach 64 and then cause the elevation of the rack frame 50. Guides 65 serve to keep the rack 5 frame 50 in its true alignment.

A gear 66 is fixed upon the shaft 59 and is adapted to engage one or the other of the rack surfaces 51 and 52 of the frame 50. The rotation of the gear 66 in a clockwise direction in Figure 3, causes the rack frame 50 to be moved toward the right and exert a pull upon the brake lever 44. The brake valve of the air line 45 is thus opened and the brakes of the train caused to be applied. The shaft 59 is extensibly mounted in a socket 67 of a worm shaft 68.

The worm shaft 68 has bearings 69 and 70 as shown in Figures 2 and 3. The shaft 68 has a worm pinion 71 with which a worm gear 72 upon the shaft of a motor 73 meshes. The energization of the motor 73 causes the shaft 59 to rotate and effect the reciprocation of the frame 50.

The shaft 59 is also provided with a spring 74 which is coiled thereabout, and is housed in a recess 75 in the end of the shaft 68. The spring 74 engages the base of the recess 75, and also an abutment on the shaft 59 so that the shaft 59 and the gear 66 may be held in a normally forward position. When the frame 50 is moved forwardly toward the right as previously explained, so that the cam guide 57 engages the end of the shaft 59, the shaft 59 is by this engagement moved laterally so that the gear 66 disengages the teeth of the rack 51 with which it will be in engagement, so that a change in the adjustment of the frame 50 may effected whereupon the gear 66 is again moved into engagement with the rack 50 but at this time with the lower rack surface 52. The change in the engagement of the gear 66 is effected by the curved beak 58.

A current strip 76 is embedded in a suitable dielectric frame 77 mounted upon the rack frame 50. The current strip 76 has insulated portions 78 over which a contact arm 79 forming one terminal of the motor 73 is adapted to move. The contact arm 79 is mounted upon the journal 69 from which it is suitably insulated as shown in Figure 2. A binding post 80 on the contact arm 79 is connected with the motor 73 by a wire 81. The other terminal of the motor 73 is connected by a wire 82 to the transformer 9 of the battery 11.

The motor 73 is energized by the completion of an electric circuit from the battery 11 through the wire 83, a pair of switch terminals 84 in the automatic switch box 35, the wires 83, the current strip 76, the contact arm 79, the wire 81, and the wire 82 back to the battery 11, when the switch 33 65 is in engagement with the switch terminals

84 as shown in Figure 5. The switch arm 33 reaches the position between the switch contact 84 as shown in Figure 5, when the contact 22 and 26 on the semaphore arm 19 and standards 12 respectively are separated 70 and spring 86 attached to post 87 and the rack 50. This spring 86 will continue to move the rack to the right until the cam 60 raises the rack sufficiently so that the gear 66 meshes with the teeth 52". When the contacts 22 and 26 are separated, it means that the semaphore 19 is located at a danger indication position. The consequent energization of the motor 73 as above explained, causes the rotation of the gear 66 and the consequent operation of the lever 44 to open the air brake line.

A solenoid magnet 88 is embraced in a portion of the motor operating circuit represented by the wires 85, and the solenoid 85 magnet 88 is adapted to force a core 89 inwardly when it is energized. The core 89 is connected with a miniature semaphore arm 90 and is a replica of the semaphore arm 19 upon the roadway.

The position of the semaphore arm 90 can be seen by the engineer in the cab of the locomotive, through a pane 91 in a semaphore box 92. The position of the semaphore 90 is further rendered visible at night, 95 by a red window 93 which may be suitably illuminated when the semaphore arm 90 is in a danger indicating position shown in Figure 4. The weight of the semaphore arm 90 causes it to return to its downward 100 or safety indicating position when the solenoid magnet 88 is deenergized as when the semaphore arm 19 is in its safety indicating position thus bring the contacts 22 and 26 into engagement and energizing the electro- 105 magnet 37 in the automatic switch box 35.

The operation of the device is as follows: Let it be assumed that for some reason the semaphore arm 19 may have been moved to a danger indicating position as indicated in Figures 1 and 7, and that a locomotive 1 is approaching the block thus indicated. When the semaphore arm 19 is thus shut, the contacts 22 and 26 on the arm 19 and the standard 12 respectively, are separated 115 and the local circuit flowing from the battery 24 is broken.

When the local circuit is broken, the electromagnet 37 is deenergized and the switch arm 33 is drawn over to the position indicated in Figure 5 by the spring 38. The switch arm 33 will thus enter the contacts 84 and close the train circuit. The circuit thus closed flows from the positive pole of the battery 11 over the wire 33 to the contacts 84. The current then flows from the contact 84 over the wire 85, through the solenoid magnet 88, over the wire 85 to the current strip 76, into the contact arm 79, over the wire 81 to the motor 73, and from 130

the motor 73 over the wire 82 to the negative terminal of the battery 11. The motor 75 thus being energized causes the rotation of the gear 66 in a clock-wise direction.

5 By reference to Figure 3 it will be observed that the clock-wise rotation of the gear 66 will cause the movement of the rack frame 50 in a direction toward the right. At this time the shaft 59 of the gear 66 will 10 rest upon the guide 55 and the gear 66 is in engagement with the rack surface 51. The movement of the rack frame 50 toward the right will pull the brake lever 44 through the medium of the link 46.

15 The air line 45 is then opened and the train brake set. The rotation of the gear 66 will continue and when it reaches the curved portion 56 of the guide 55, the shaft 59 will be pressed outwardly against the 20 tension of the spring 74 by the cam guide 57. The shaft 59 will now roll over the curved guide 56 and being supported by the curved beak 58 will be suitably guarded so that the gear 66 may come into proper engagement 25 with the lower rack 52. The rack 52 will come into engagement with the gear 66 by reason of the engagement of the cam 60 with the approach 64 and the pull of the spring 86. It will be understood 30 that when the rack frame 50 has moved far enough toward the right to effect the interchange of the rack and gear engagement as above outlined, the cam 60 will also have reached the approach 64 and the cam 60 will ride upon the approach 64 35 causing the elevation of the frame 50.

When the frame 50 reaches its extreme 40 position toward the right, the contact arm 79 will have moved over the insulated portions 78 momentarily causing the stopping of the motor 73 by reason of the opening of the motor circuit at this point. The lower rack 52 is now in engagement with the gear 66 and the lower portion of the current strip 45 76 is in engagement with the contact arm 79.

The motor circuit being closed the rotation of the gear 66 will continue and since the gear 66 is now in engagement with the lower rack 52 the rack frame 50 will be 50 moved toward the left thus returning the brake lever 44 to its normal or closed position. The operation of the brake lever 44 through the medium of the rack frame 50 will in actual practice be rather slow, no 55 faster than the manual operation thereof would be accomplished. It will thus be seen that the brake lever 44 and consequently the valve 43 is slowly opened and then slowly closed which will cause the gradual 60 application of the air brakes of the train.

Let it now be assumed that the train has passed out of the block wherein the semaphore arm 19 is at a danger indicating position and into a block where the semaphore 65 arm 19 is at a safety indicating position.

When the semaphore arm 19 is at a safety indicating position, the contacts 22 and 26 will be in engagement and this portion of the local circuit from the battery 24 will be closed. When the locomotive 1 carrying 70 the trolley 29 engages the wire 17, the current from the positive pole from the battery 24 will flow over the wire 23 to the contact 22, from the contact 26 over the wire 28 to the line wire 17, through the trolley 29 and 75 arm 30 to the electromagnet 37, from the electro-magnet 37 over the wire 41 to the axle 3, through the axle 3, wheel 2 and rail 4 returning to the negative pole of the battery 24 through the wire 25.

80 The electromagnet 37 being thus energized will attract the armature 36 and brace the circuit between the switch arm 33 and the contact 34. The local or train circuits being thus broken at the contact 84 will be inoperative and as a consequence the motor 73 will not actuate the rack frame 50. The 85 brake valve 43 is thus not affected and the air brakes of the train will not be applied.

While the construction and arrangement 90 of the device as illustrated and described is that of a generally preferred form, obviously modifications and changes may be made without departing from the spirit of the invention or the scope of the claims. 95

I claim:—

1. In a train control mechanism, the combination with the air brake lever and valve, of a rack frame joined with the air brake lever including an upper and lower rack, a gear engageable with the upper rack adapted upon rotation to reciprocate the frame forwardly, a motor for rotating the gear, a circuit including a battery and a pair of contacts, a switch arm adapted to engage 105 the contacts to close the motor circuit, and means for causing the engagement of the lower rack with the gear to reciprocate the frame rearwardly.

2. In a train control mechanism, the combination with the air brake lever and valve, of a rack frame joined with the air brake lever including an upper and lower rack, a gear engageable with the upper rack adapted upon rotation to reciprocate the frame 110 forwardly, a motor for rotating the gear, a circuit including a battery and a pair of contacts, a switch arm adapted to engage the contacts to close the motor circuit, means for causing the engagement of the lower 115 rack with the gear to reciprocate the frame rearwardly, and means for guiding the gear shaft.

3. In a train control mechanism, the combination with the air brake lever and valve, of a rack frame including an upper and lower rack the frame being joined with the air brake lever, a gear shaft having a gear in engagement with the upper rack, a motor 125 for rotating the gear shaft to cause the 130

reciprocation of the rack frame forwardly, the current strip including upper and lower portions, a contact in engagement with the portions, an electric circuit embracing the 5 motor and the contact strip said circuit having a battery and a pair of contacts, a switch arm adapted to close the contacts, and means for transferring the engagement of the gears and the contact arms to the 10 lower rack and current strips respectively.

4. In a train control mechanism, the combination with the air brake lever and valve, of a frame joined with the air brake lever and including upper and lower racks, a 15 gear adapted to engage the upper rack, a motor for rotating the gear to move the frame forwardly, a current strip including upper and lower portions carried by the frame, a contact arm adapted to engage the 20 upper portion, insulated blocks at the ends of the current strip portions, a motor circuit including contacts and a source of energy, a contact arm adapted to engage the contact to close the circuit, the contact arm being adapted to engage one of the insulated 25 portions of the current strip upon the reciprocation of the frame in the forward direction, and means for simultaneously causing the engagement of the contact arm 30 with the lower strip portion and the engagement of the lower rack with the gear.

5. In a train control mechanism, the combination with the air brake lever and valve, of a frame joined with the air brake lever 35 and including upper and lower racks, a gear adapted to engage the upper rack, a motor for rotating the gear to move the frame forwardly, a current strip including upper and lower portions carried by the frame, a 40 contact arm adapted to engage the upper portion, insulated blocks at the ends of the current strip portions, a motor circuit including contacts and a source of energy, a contact arm adapted to engage the contact 45 to close the circuit, the contact arm being adapted to engage one of the insulated portions of the current strip upon the reciprocation of the frame in the forward direction, means for simultaneously causing the 50 engagement of the contact arm with the lower strip portion and the engagement of the lower rack with the gear, said means comprising a spring.

6. In a train control mechanism, the combination with the air brake lever and valve,

of a frame joined with the air brake lever and including upper and lower racks, a gear shaft having a gear adapted to engage the upper rack, motor connections for rotating the gear to drive the frame forwardly, 60 a guide on the frame for the gear shaft, a dielectric support on the frame having a current strip including upper and lower portions ending in insulated blocks, a contact arm adapted to engage the upper portions, a motor circuit including a source of energy and a pair of contacts, a switch arm adapted to engage the contacts to close the motor circuit, cam devices for elevating the frame to simultaneously cause the engagement of the lower rack with the gear and the lower strip portion with the contact and the end of the forward thrust of the frame, and a cam guide for the end of the gear shaft. 75

7. In a train control mechanism, the combination with the air brake lever and valve, of a frame having link connections with the air brake lever and including an upper and lower rack, a base for the frame including a track and a cam approach, a cam on the frame, a gear shaft having a gear adapted to engage the upper rack, a motor and connections for rotating the gear to drive the frame forwardly, a motor circuit 80 including a source of energy and closing means therefor, a guide for the gear shaft, a cam guide for the end of the gear shaft for guiding the shaft when the frame cam reaches the track approach to cause the 85 engagement of the lower rack with the gear, and resilient supporting means for the gear shaft.

8. In a train control mechanism, the combination with the air brake lever and valve, 95 of a shiftable frame connected with the air brake lever, motor actuated means for reciprocating the frame forwardly and rearwardly to open and close the valve, a local motor circuit including a source of energy 100 for energizing the motor, externally operated means for controlling the opening and closure of the motor circuit, and an indicating means in the motor circuit.

In testimony whereof I affix my signature 105 in presence of two witnesses.

JOHN P. ANGUS.
